UNITED STATES PATENT OFFICE.

EDWIN J. TOOF, OF NEW HAVEN, CONNECTICUT.

DESIGN FOR A SADDLE POMMEL-PLATE.

SPECIFICATION forming part of Design No. 26,030, dated September 15, 1896.

Application filed July 27, 1896. Serial No. 600,716. Term of patent 7 years.

To all whom it may concern:

Be it known that I, EDWIN J. TOOF, a citizen of the United States, and a resident of the city and county of New Haven, State of

5 Connecticut, have invented and produced a new and original Design for a Saddle Pommel-Plate, of which the following description, taken in connection with the drawings here-
with accompanying, is a specification.

10 Referring to the drawings, Figure 1 represents a perspective view of a plate embodying my design, and Fig. 2 represents a side elevation of the same.

My invention relates to a design for pom-
15 mel-plates for saddles, and more particularly for bicycle-saddles; and it consists in the configuration of the same, as hereinafter de-
scribed and as shown in the accompanying illustrations. This plate presents a some-

20 what elongated and substantially flat upper surface throughout parts of its length, as at *a*, and at one end thereof extends in a direc-
tion at substantially right angles to said up-
per surface, as at *b*, the straight lines of the
25 surfaces *a* and *b* being merged or united by
a curved line *c*. The opposite edges *d d* of
this plate extend from the flattened surface *a*

at a point back from the end *b* to the lower edge of the latter at an angle to the line of the surfaces *a* and *b*, as clearly shown in the drawings. The surface of the plate between the opposite angularly-extending edges *d d* in cross-section extends in a curved line from said edges *d d* toward the center of the plate, and this curved surface is of varying width 35 from a continuous curved line at the end of the plate until it merges into the surface *a* toward the end of the angular edges *d d*, as clearly shown.

That portion of the plate above described 40 embodies the leading feature of my design. At the opposite end of the plate the sides thereof extend outward at substantially right angles to the length of the plate, as at *e e*, and then extend in converging lines *e' e'* until 45 they merge into each other at *e' e'*.

What I claim is—

The design for a saddle pommel-plate as herein shown and described.

EDWIN J. TOOF.
